UNITED STATES PATENT OFFICE.

WALTER H. SMITH, OF PITTSBURGH, PENNSYLVANIA, ASSIGNOR TO MILLER SAW-TRIMMER COMPANY, A CORPORATION OF PENNSYLVANIA.

AUTOMATIC PRESS-FEEDING DEVICE.

1,331,392.

Specification of Letters Patent.

Patented Feb. 17, 1920.

Application filed May 14, 1919. Serial No. 297,066.

To all whom it may concern:

Be it known that I, WALTER H. SMITH, a subject of the King of England, residing at Pittsburgh, in the county of Allegheny and 5 State of Pennsylvania, have invented certain new and useful Improvements in Automatic Press-Feeding Devices, of which the following is a specification.

My invention pertains to automatic feeding devices for printing presses, and relates 10 especially to press feeders for attachment to what are known as job presses, particularly those of the Gordon type.

Where an automatic feeding device is applied to a printing press, the mechanism of such feeder has often to be so placed in such a position that it would be in the way of an operator attempting to make the press ready, in the usual way, for printing a job. 20 This difficulty may be overcome by constructing the feeder in such a manner that it, or a part of it, can be moved out of the way when desired, thus permitting the pressman to effect his "make ready" in the manner

25 to which he is accustomed, the objection to this being that if the feeding parts are moved laterally extra lateral shop space is needed for the machine, whereas vertical moving is made difficult by the bulk and 30 weight of the parts. With these conditions in view, it is one of the objects of my invention to provide an automatic feeder, a portion of which may be swung vertically upward about a hinge, and to provide means 35 for compensating for the weight of such portion, thus to enable the swinging operation to be easily accomplished. It is another object of my invention to provide a simple means for the release and return of

40 the weight compensating device, so as to facilitate the complete removal of the swinging portion when such removal is desired. It is another object of my invention to provide a simple, strong and reliable device 45 for locking the feeding mechanism carried by the swinging portion in proper timing relation when swung out of operative relation with the press. Another object of my invention lies in the provision of means for 50 permitting a proper spacing relation to be insured between the gears of the mechanism carried by the swinging portion, and between such gears and the press gear from

which the feeding mechanism is driven. Still other and further objects will appear 55 from the following specification and the claims forming part thereof.

I have described, by way of example, in the following specification, and shown in the accompanying drawings, one embodiment of my invention as applied to a press feeder of the general type forming the subject of Patent No. 1,145,405 granted July 6th, 1915, to Edward Cheshire. It is to be understood, however, that my invention may 60 be embodied in other forms, and that changes may be made in the form described and shown, without exceeding the scope thereof, as defined in the appended claims.

In the drawings:

Figure 1 is a perspective view showing the hood portion of the feeding device swung up to provide for make-ready, hand feeding or the like;

Fig. 2 is a perspective view taken from 75 the opposite side, showing the hood portion in operative relation with the press;

Fig. 3 is a detail perspective view of the means for locking the feeder mechanism against movement when such mechanism is 80 swung out of operative position;

Fig. 4 is a side view showing the main driving gear of the feed mechanism and the means for adjusting the intermediate gear to provide proper spacing relation; and 85

Fig. 5 is a section taken on the line 5—5 of Fig. 4, looking in the direction of the arrows.

Referring now to the drawings, 6 designates the base of a feeder of the type disclosed in Letters Patent No. 1,145,405 above referred to. This base is attached by suitable connecting devices to an existing press and carries an automatically elevated stock table 7 for supporting the pile of sheets 95 which are to be fed one by one to the press by the feeding mechanism. The feeding mechanism is carried by a hood 3 having a pair of separated lugs 9, 10 which embrace between them a pair of lugs 11, 12 extending laterally from the base 6. A pin 13, having a knurled head 14 to facilitate grasping, passes through aligned holes in the lugs 9, 11, 10, 12, thereby permitting the hood to be swung up, about the pin 13 as a pivot, 100 from the position shown in Fig. 2 to the in-

operative position shown in Fig. 1. The base 6 is provided with a lateral extension 15 having a spring-pressed plunger 16 extending upwardly therefrom. When the hood 8 is swung upward somewhat beyond its dead center, a portion 17 thereof strikes upon the plunger 16, the latter forming a cushioning device preventing the hood from coming too suddenly to rest against the extension 15.

The base 6 is formed with a recess 18 which communicates with the space between the lugs 11 and 12. Extending across the recess 18 is a removable pin 19, upon which 15 rests one end 20 of a coil spring 21. The coil spring 21 surrounds the pin 13 and engages with its other end 22, in a notch formed in an ear 23 which extends downwardly from the hood 8. The spring 21 20 tends always to raise the hood about its pivot, but is not of sufficient strength to actually do this. It thus has the effect of making the manual raising of the hood an easy operation, the manual strength exerted 25 remaining practically constant throughout the entire swinging operation, since the power exerted by the spring decreases proportionately to the distance through which the hood is swung upward. When it is desired to remove the hood from the base, this 30 may easily be effected by swinging it up to the position shown in Fig. 1, whereupon the pin 19 can readily be removed, as the spring is then under little strain. The spring, of course, becomes inactive upon the pin 19 35 being taken out. After swinging the hood down again, without the counterbalancing help of the spring, the pin 18 may be withdrawn and the hood removed from the base.

40 When the hood is replaced the spring is reset, with the pin 19 beneath its end 20. This is readily accomplished when the hood is in the position shown in Fig. 1, as the spring then exerts but little power.

45 In order that assurance may be had that the timing relation with the press will be correct when the hood is replaced in operative position after being swung up for make-ready or the like, means are provided for 50 locking the mechanism carried by the hood against movement as soon as the hood is swung away from the base. This locking means includes a bar 24 which is slidably mounted in the hood and is adapted to engage with its end in the teeth of one of the gears 25 of the feed mechanism. The bar 24 has formed thereon a pair of collars 26 55 between which engages the forked end of one arm 27 of a lever 28. The lever 28 is pivoted upon a pin 29 carried by the ear 23 of the hood 8 and has a short arm 30 extending substantially at right angles to the arm 27. Interposed between the end of the short arm 30 and the adjacent portion of 60 the hood 8 is a spring 31, which tends to 65

force the end of the bar 24 into engagement with the teeth of the gear 25. An abutment 32 projects upward from the base 6 in such a position as to engage the arm 30 when the hood is swung down into operative position for the feeding mechanism, thereby shifting the lever 28 about its pivot and withdrawing the bar 24 from engagement with the gear 25. So long, therefore, as the hood is in operative position on the 75 base the feed mechanism can run freely; but as soon as a start is made to swing the hood up upon its pivot, the arm 30, leaving the abutment 32, is pushed down by the spring 31, the end of the bar 24 being thereby forced between the teeth of the gear 25. The feed mechanism is thus locked in proper timing relation during the time it is out of operative position.

To insure that the feed mechanism, after 80 being swung up, shall be in proper timing relation with the press itself when replaced, the hood 8 has formed thereon a beveled lug 33 so placed that, although it is clear of the teeth of the bull wheel 34 of the press both in the raised and normal positions of the hood, it will strike against the teeth of the bull wheel if an attempt is made to move the hood except in one position of the press. In this one position of the press, the lug 33 85 can pass through a space 35 created by cutting away a portion of one of the teeth of the bull wheel 34. Thus it is impossible to replace the hood in operative position except when the feed mechanism is in correct timing relation with the press itself. In order to indicate to the operator when the notch 35 of the bull wheel has come opposite the lug 33, a mark 36 is made on one 90 of the wheels 37 of the press, this mark being so placed that when it comes opposite a finger 38, carried by the base 6, the parts are in correct position for the raising of the hood.

In a device of this character it is highly 95 desirable that the parts of the feeder shall run smoothly and in accurate relation with the parts of the press. Any material back-lash in the gears would be likely to cause trouble. This presents an important problem, especially where the feeder is to be attached to existing presses, the gears of which may be new or may have become worn, or even if new, will vary within noticeable limits. In order to obviate back-lash and at 100 the same time permit the feed mechanism to be swung into and out of operative relation with its base, I make the gear 25, which engages with the bull wheel 34, in the form of an anti back-lash gear, that is a gear 105 made in two sections 25^a and 25^b which can be adjusted in a circumferential direction relatively to each other, thereby taking up any play or back-lash which might otherwise exist between the gear 25 and the bull 110

wheel 34. The gear 25 is mounted to rotate on a stud 36 having bearing portions 37 and 38 fitting in suitable bearings carried by the casing 39 of the hood, the stud being 5 slightly eccentric with respect to said bearing portions. One of the bearing portions, 37, is formed with a slot 40 for receiving a screw driver or the like and is adapted to be locked in any desired position of rotation by 10 means of a set screw 41. The gear 25 has secured thereto a pinion 42 with which meshes a gear 43 carried by a shaft 44, which latter shaft constitutes, in effect, the main drive shaft of the feeder.

15 Supposing that, prior to adjustment, the axis of the stud 36 is in line with the axis of the bearing portion 37 and the axis of the shaft 44, then if it be desired to bring the pinion 42 closer to the gear 43, in order 20 that their pitch lines may coincide, this may be effected by rotating the bearing portion 37 so that the stud 36 is brought into a position such as is shown in Fig. 4, and thereafter securing it again by means of the set 25 screw 41. This will, of course, bring the gear 25 nearer to the bull wheel 34. If it is found that the gear 25 is then too close to the bull-wheel, the bearing portion 37 may be rotated into a similar position to that 30 shown in Fig. 4 but with the axis of the stud 36 above that of the bearing portion 37, instead of below it as shown. The gear 25 will then be farther from the bull-wheel. Any play existing between the gear 25 and 35 the bull wheel can be taken up by an adjustment of the anti back-lash members 25^a and 25^b of the gear 25. In the above manner I am enabled to obtain a perfect drive from the bull wheel 34 to the shaft 44, in spite of 40 any variation or wear in the teeth of the bull wheel, or variation in the spacing of the shaft 44 and stud 36.

By the means above described, I have produced a press feeding device, the feeding 45 mechanism of which may be swung up, when it is desired to get at the press for a make ready or the like, into a vertical position wherein it does not intrude upon shop space useful for other purposes. The operation 50 of swinging the feeding mechanism up and down can be effected with the exertion of little strength, and there is no danger of the operator being forced to let the device drop or otherwise treat it roughly. The feeding 55 device cannot be swung either up or back except in one particular position of the press parts, and the feed mechanism becomes effectually locked, against movement out of proper timing, as soon as it is moved from 60 its operative position. The gearing between the feeding mechanism and the press is constructed so as to admit of the swinging away of the former and to run smoothly and evenly, without play or back-lash.

65 Having thus fully described my said in-

vention, what I claim as new, and desire to receive by Letters Patent, is:

1. The combination with a platen press, of a head movably supported with relation to the press and carrying automatic feeding 70 mechanism, means to compensate for the weight of the head in movement, and means for releasing the compensating means and separating the head from the press.

2. The combination with a platen press, 75 of a feeder mechanism head, a pivot pin connecting the head and press to permit a swinging movement of the head with respect to the press, a spring coiled about said pin and having one terminal bearing against 80 the head, and removable means associated with the press to receive the other terminal of the spring.

3. The combination with a platen press, 85 of a feeder mechanism head, a pivot pin connecting the head and press to permit a swinging movement of the head with respect to the press, a spring coiled about said pin and having one terminal bearing against 90 the head, and a removable pin associated with the press to support the other terminal of the spring.

4. The combination with a printing press of mechanism for use in feeding sheets thereto, means for connecting said mechanism to said press so as to be movable in a substantially vertical plane into and out of operative relation therewith, means for compensating for the weight of said mechanism during movement, and means for releasing 100 the compensating means and separating the feeding mechanism from the press.

5. In combination, a printing press, an abutment member removably associated with said press, mechanism for use in feeding sheets to said press, means for hingedly connecting said mechanism to said press so as to be swingable in a substantially vertical plane into and out of operative relation therewith, and a coil spring engaging 110 with one end against said mechanism and with the other end against said removable abutment.

6. In combination, a printing press, mechanism associated with said press for use in 115 feeding sheets thereto, and movable into and out of operative relation therewith, a bar slidably associated with said mechanism, means tending to move said bar into engagement with a moving part of said mechanism 120 thereby to lock said mechanism against movement, and means preventing the operation of said last-named means when said mechanism is in operative relation with said press.

7. In combination, a printing press, mechanism associated with said press for use in feeding sheets thereto and movable into and out of operative relation therewith, said mechanism including a gear wheel, a bar 130

slidably associated with said mechanism, means tending to move said bar into engagement with the teeth of said gear, thereby to lock said mechanism, and means preventing the operation of said last-named means when said mechanism is in operative relation with said press.

8. In combination, a printing press, including a gear wheel, and mechanism for use in feeding sheets to said press movable into and out of operative relation therewith, said mechanism including a driven gear, an intermediate gear actuating said driven gear and disposed to engage said first-named gear wheel when said mechanism is in operative position, and bearing portions for said intermediate gear eccentric to the axis thereof.

9. In combination, a printing press including a gear wheel, and mechanism for use in feeding sheets to said press, said mechanism including a driven gear, an intermediate gear actuating said driven gear and disposed to engage said first-named gear wheel when said mechanism is in operative position, said intermediate gear having two sets of teeth circumferentially adjustable with respect to each other, and bearing portions for said intermediate gear eccentric to the axis thereof.

10. In combination, a printing press, mechanism associated with said press for use in feeding sheets thereto, and movable into and out of operative relation therewith, locking means adapted to engage a moving part of said mechanism, and means

preventing the operation of said last-named means when said mechanism is in operative relation with said press.

11. In combination, a printing press, feeding mechanism, means coöperating with a moving part of the printing press to insure registration of the coöperating mechanisms after the feeding mechanism has been moved, means for automatically locking a moving part of the feeding mechanism when the same is moved to inoperative position, and means between the feeding mechanism and the press to release the locking means when the feeding mechanism is in operative position.

12. In combination, a printing press, a feeding head hinged to the printing press, a lock coöperating with a movable part of the feeding head to prevent movement of said parts when the head is in inoperative position, and intermediate means carried by the head to engage a fixed part of the press to release the lock when the feeding mechanism is in operative position.

13. In combination, a printing press, feeding mechanism for said press, gearing between said printing press and feeding mechanism, including two sets of teeth circumferentially adjustable with respect to each other, and bearing portions for one of said gears eccentric to the axis thereof.

In testimony whereof I affix my signature.
WALTER H. SMITH.
